UNITED STATES PATENT OFFICE.

BERNARD THOMAS LEVEQUE, OF WENHAM, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BUTTON-ATTACHING MACHINE.

1,290,253.

Specification of Letters Patent.

Patented Jan. 7, 1919.

Original application filed July 17, 1916, Serial No. 109,694. Divided and this application filed January 18, 1917. Serial No. 143,042.

To all whom it may concern:

Be it known that I, BERNARD T. LEVEQUE, a citizen of the United States, residing at Wenham, in the county of Essex and Commonwealth of Massachusetts, have invented certain new and useful Improvements in Button-Attaching Machines; and I do hereby declare the following to be a full, clear, and exact description of the invention, such as will enable others skilled in the art to which it appertains to make and use the same.

The invention relates to button attaching machines, and more particularly to the means for feeding buttons to the button attaching mechanisms of such machines.

This application is a division of application Serial No. 109,694, filed July 17, 1916.

The object of the invention is to provide novel and efficient means for supplying buttons to a button chute and for positioning them at the delivery end of the chute, and to otherwise improve the button feeding mechanism. To these ends the invention comprises the features of construction and combinations of parts hereinafter described and referred to in the claims.

The invention will be readily understood from an inspection of the accompanying drawings and the following detailed description of the mechanism illustrated therein.

In the drawings, Figure 1 is a front elevation of a machine for sewing on buttons embodying the invention in its preferred form; Fig. 2 is a sectional view through the button hopper on line 2, Fig. 1; Fig. 3 is a side elevation showing the lower end of the button chute; Fig. 4 is a sectional view on line 4, Fig. 3; Fig. 5 is a sectional view on line 5, Fig. 3; Fig. 6 is a vertical sectional view through the center of the button delivery hopper and button chute; Fig. 7 is a plan view of the parts shown in Fig. 6; Fig. 8 is a detail view showing the lower end of the button chute; Fig. 9 is a detail view looking toward the right in Fig. 8; and Fig. 10 is a sectional view on line 10, Fig. 7.

In the drawings the invention is shown embodied in a machine in which the button attaching mechanism comprises a vertically

reciprocating and laterally movable eye pointed needle 2 and looper fingers 4 which cooperate with the needle in passing a primary loop through the work and through a button eye, passing a secondary loop through the work and through the primary loop outside the eye, and passing the secondary loop over the button head. The button is fed into position for the passage of the needle through its eye by a button chute which is swung in the line of feed to withdraw the partially attached button from the chute, and to push the button through the secondary loop as it is passed over the button head.

The button chute comprises a front plate 6 grooved to permit the passage of the button shank, and provided at its lower end with two positioning plates 8. The plates 8 are spaced to provide a shank slot between them which curves to present the button shank of the lowermost button in the chute in a horizontal plane. The button heads are supported as the buttons pass down the chute by a back plate 10 which is secured to the front plate by screws 12 passing through lugs in the back plate which are slotted so that the back plate may be conveniently adjusted toward and from the front plate in accordance with the size or thickness of the heads of the buttons being operated upon. The lowermost button is positioned in the lower end of the chute by a stop 14 which is engaged by the head of the button and by a clamp 16, which presses the head of the button, after it has engaged the stop, snugly against the positioning plate 8. As shown, the button clamp 16 is provided with a trunnion 18 mounted in bearings formed in a bracket 20 secured to the lower end of the back plate 10. The clamp is forced in a direction to disengage the button head by a torsional spring 22. The clamp is provided with an upwardly projecting spring arm 24, the upper end of which is bent to form a cam 26 which is arranged to engage a fixed roll 28 as the button chute swings into button presenting position. The button stop 14 is pivoted on the clamp 16, and is held normally in position by a torsional spring 30. The stop is provided with 100

a laterally projecting lug 32 which carries an adjusting screw 34 arranged to engage the rear side of the button clamp, and to determine the position of the stop with relation 5 to the front face of the clamp.

- When the chute is in button presenting position, as indicated in Figs. 3, 4 and 5, the cam 26 is in engagement with the roll 28, and the clamp is forced yieldingly forward 10 to press the button laterally against the positioning plates 8. When the button chute is swung toward the right to withdraw the button from the chute as above described, the button stop yields to permit the button 15 to pass from the end of the chute, and as the movement of the chute toward the right continues, the cam 26 disengages the roll 28, so that the clamp is swung by the spring 22 back out of the path of the buttons. The 20 lowermost button in the chute then passes down against the stop, where it is in proper position to be carried by the forward movement of the chute into position for the passage of the needle through its shank. The 25 button engaging face of the stop 14 is arranged at substantially an angle of 45° to the plane of the positioning plates, and will properly locate any size of buttons having substantially hemispherical heads, the adjustment of the back plate for any size of button head bringing the stop into proper relation to the positioning plates to correctly locate the button in the chute. In case the machine is to operate upon "Milo" buttons, 30 or similar buttons having flat or disk-shaped heads, an adjustment of the button stop with relation to the clamp will be required, and the proper adjustment may be readily secured by turning the adjusting screw 34.
- 40 The button chute is supported by a trunnion 36 formed in line with its upper end and engaging a bearing 38 on the head of the machine. The proper swinging movements are given to the chute to position and 45 withdraw the lowermost button, and to advance and retract the button bushing fingers 40 through a link 42 connecting the lower end of the chute with an arm 44 which is secured to the forward end of a rock shaft 50 46. The rock shaft is actuated through suitable connections from a cam on the cam shaft.

The buttons are supplied to the upper end of the raceway from a small delivery hopper 55 48 which is provided on its lower side wall with a button delivery opening 50 shaped to receive a button and forming the mouth of a short guideway 52 which registers with the shank guiding slot of the button chute 60 and ends at the axis of the trunnion 36. The lower end of the supply hopper is closed by a base or back plate 54 which registers with 10 and forms a continuation of the back plate

secured to the hopper by a screw 56 which 65 passes through a slot in a guiding lug 58 projecting from the base plate and guided between ribs on the side of the hopper. The base plate may be readily adjusted for different sizes of buttons, or may be dropped 70 sufficiently to enable all the buttons in the hopper to be discharged between the lower edge of the hopper and the plate. A button agitating brush 60 is mounted within the hopper to play across the delivery opening 75 50. The brush is secured to the lower end of a shaft 62 which extends up through a bearing in the top of the hopper and carries a pinion 64 at its upper end. The pinion is engaged by a gear segment 66 secured to 80 the upper end of the button chute trunnion 36 so that the agitator brush is oscillated by the oscillation of the chute. The pinion is clamped against a shoulder on the shaft 62 by a cam lever 68 pivoted on the upper end 85 of the shaft 62. This lever may be turned by the operator to free the pinion from the shaft, and thus permit the brush to be agitated by hand if desired.

The buttons are supplied to the delivery 90 hopper 48 from a large supply hopper 70 arranged at one side of the delivery hopper and communicating therewith through a supply opening 72 arranged in the side wall of the delivery hopper above and out of line 95 with the delivery opening 50. With this construction and arrangement a large supply of buttons may be carried in the supply hopper 70 and be gradually delivered into the delivery hopper 48 without packing 100 the buttons closely in the delivery hopper, or in such manner as to clog or interfere with the agitation of the buttons within the delivery hopper by the agitator brush. Since the supply opening through which the buttons pass to the delivery hopper is formed in the side of the delivery hopper, and out of line with the delivery opening through which the buttons are fed to the chute, the buttons will not completely fill the delivery hopper, 110 and as the space within the hopper is comparatively small, the loose mass of buttons will not press upon the agitator in such manner as to interfere with its proper and efficient action. The upper rear wall of 115 the supply hopper is preferably so shaped that it will retain the buttons within the hopper when the frame of the machine is tipped up to give access to the cam shaft and parts carried by the machine base.

While it is preferred to employ the specific construction and arrangement of parts shown and described in constructing a machine embodying all the features of the invention in their preferred forms, it will be 125 understood that this specific construction and arrangement of the parts is not essential to the broader features of the invention, but

may be varied or modified as found desirable or best suited to the construction and arrangement of the coöperating parts of the machine in which any feature of the invention is to be embodied.

Having explained the nature and object of the invention, and specifically described one form of machine in which it may be embodied, what is claimed is:—

10. 1. A button attaching machine, having, in combination, button attaching mechanism, a button chute, a hopper provided with a delivery opening through which individual buttons are delivered by gravity to the chute and with a lateral supply opening in its side wall above and out of line with the delivery opening, and a supply hopper for delivering buttons through the supply opening.

2. A button attaching machine, having, in combination, a button chute, a hopper provided with a delivery opening through which individual buttons are delivered to the chute, a button agitator working across the delivery opening, and a supply hopper at one side of the delivery hopper and communicating therewith through an opening in the side wall of the delivery hopper approximately at right angles to the delivery opening.

3. A button attaching machine, having, in combination, a button attaching mechanism, a stationary hopper having an outlet, a vibrating chute for conducting buttons from the outlet to the attaching mechanisms, an agitator in the hopper, and connections for actuating the agitator from the chute.

4. A button attaching machine, having, in combination, button attaching mechanism, a button chute for presenting buttons to the attaching mechanism, a button clamp at the end of the chute, a yielding button stop having an inclined face, and adjusting means for determining the extent to which the stop projects beyond the face of the clamp.

5. A button attaching machine, having, in combination, button attaching mechanism, a button chute provided with an adjustable back plate, a button clamp and a yielding button stop having an inclined face both mounted on the back plate, and means for adjusting the stop with relation to the face of the clamp.

6. A button attaching machine, having, in combination, button attaching mechanism, a button chute for presenting buttons to the attaching mechanism, a button clamp at the end of the chute, a button stop having an inclined face mounted on the clamp, and an adjusting screw on the stop engaging the clamp and determining the extent to which

the stop projects beyond the face of the clamp.

7. A button attaching machine, having, in combination, button attaching mechanism, a button chute provided with an adjustable back plate, a hopper for delivering buttons to the chute provided with a base plate forming a continuation of the back plate and the chute, and means whereby the hopper back plate may be adjusted for different sizes of buttons or dropped sufficiently for the discharge of the buttons in the hopper between the base plate and lower edge of the hopper.

8. A button attaching machine, having, in combination, button attaching mechanism, a button chute comprising a front plate having a shank slot and an adjustable back plate provided with slotted lugs on the front side of the chute, screws connecting the lugs with the front plate, a hopper provided with a shank guiding slot registering with the slot in the front plate of the chute and with a base plate provided on its front side with a slotted lug fitting between ribs on the front side of the hopper, and a screw securing the lug to the front side of the hopper.

9. A button attaching machine, having in combination, button attaching mechanism, a button chute, a delivery hopper having an inclined base forming a continuation of the back plate of the chute and having substantially cylindrical walls, a supply hopper arranged at one side of the delivery hopper and communicating therewith through an opening in the side wall of the delivery hopper.

10. A button attaching machine, having in combination, button attaching mechanism, a button chute, a delivery hopper having an inclined base forming a continuation of the back plate and the chute and having substantially cylindrical walls, a supply hopper arranged at one side of the delivery hopper and communicating therewith through an opening in the side wall of the delivery hopper above and out of line with the entrance to the chute.

11. A button attaching machine, having in combination, button attaching mechanism, a button chute, a delivery hopper provided with a delivery opening through which individual buttons are delivered to the chute, and a supply hopper at one side of the delivery hopper and communicating therewith through an opening in the side wall of the delivery hopper, the rear wall of the supply hopper being shaped to retain the buttons when the machine is tipped up.

BERNARD THOMAS LEVEQUE.
